UNITED STATES PATENT OFFICE.

EDWARD TEMPLE, OF SPRINGFIELD, OHIO, ASSIGNOR OF ONE-HALF TO
HARRY G. REDMOND, OF REDMONDS MILLS, OHIO.

AUTOMOBILE.

No. 845,983.

Specification of Letters Patent.

Patented March 5, 1907.

Application filed February 15, 1906. Serial No. 301,125.

To all whom it may concern:

Be it known that I, EDWARD TEMPLE, a citizen of the United States, residing at Springfield, in the county of Clark and State of Ohio, have invented certain new and useful Improvements in Automobiles, of which the following is a specification, reference being had therein to the accompanying drawings.

10 This invention relates to automobiles, and has for its object, among other things, to provide a construction whereby an ordinary light road-vehicle of the type generally known as a "buggy" or "road-wagon" may be readily converted into a self-propelling vehicle or automobile.

Further objects of the invention are to provide a simple and efficient steering mechanism, to provide means whereby the speed 20 and direction of movement of the vehicle may be readily controlled in a simple and efficient manner, and to provide improved means for transmitting power to the driving-wheels while providing for relative freedom 25 of motion of said wheels to compensate for curves.

To these and other ends my invention consists in certain novel features, which I will now proceed to describe and will then particularly point out in the claims.

In the accompanying drawings, Figure 1 is a plan view, partly broken away and with the seat and hood removed, of a structure embodying my invention in one form. Fig. 35 2 is a side elevation of the same, partly broken away, to show certain details of construction. Fig. 3 is an enlarged transverse sectional view taken on the line $z z$ of Fig. 1 and looking in the direction of the arrows. 40 Fig. 4 is a detail view illustrating the driving connection between the main driving-shaft and one of the driving-wheels. Fig. 5 is a detail view of one of the clutches with the cap removed, the main driving-shaft being 45 shown in section. Fig. 6 is an enlarged detail sectional view taken on the line $y y$ of Fig. 2 and looking in the direction of the arrows. Fig. 7 is a detail sectional view taken in a longitudinal vertical plane through the 50 front portion of the vehicle, illustrating the steering mechanism. Fig. 8 is a detail plan section taken on a line corresponding to the line $z z$ of Fig. 7 and looking in the direction of the arrows illustrating the construction of

the steering-segment. Fig. 9 is a detail sectional view taken on the line $w w$ of Fig. 7 and looking in the direction of the arrows, and Fig. 10 is an enlarged detail sectional view taken in a vertical plane centrally and longitudinally through the friction-gearing. 60

In the said drawings I have shown my invention as embodied in a structure of which the basis is a light road-vehicle known as a "buggy" or "road-wagon." It comprises a box-like body 1, provided with a seat 2 and dash 3. The running-gear on which the body is mounted by means of springs 4 at the front and rear comprises a reach 5, a rear axle 6, having wheels 7, mounted to rotate thereon and constituting the driving-wheels 70 of the vehicle as modified, and a front axle 8, pivoted to turn for steering purposes by means of a pivot or fifth wheel 9 and having mounted to rotate thereon the front wheels 10, which constitute the steering-wheels. All 75 of these parts may be of any approved construction.

To the body there is connected a strengthening and supporting frame consisting of an angle bar or bars 11, bent or arranged so as to 80 form two parallel portions embracing or fitting the lower side edges of the body, being secured thereto in any suitable manner. This frame extends in front of the body to support the motor and its associated parts, said 85 extension being indicated at 12 and being preferably somewhat depressed to bring the motor to the desired level. A hood 13 (shown in position in Fig. 2 of the drawings and removed in Fig. 1) serves to cover and 90 protect the motor.

Any suitable type of motor may be employed, the form shown (indicated by the reference-numeral 14) consisting of a gasolene-motor of the opposed two-cylinder two-cycle 95 type. This motor is supported on the frame extension 12, with its main shaft 15 arranged longitudinally of the vehicle, the fly-wheel being indicated at 16. The liquid fuel is supplied to the motor from a reservoir 17, located under the body 1, at the front thereof, and connected with the motor by a supply-pipe 18. Suitable lubricators 19, mounted on the inner side of the dash 3, where they are readily accessible and plainly visible, supply 100 the lubricant to the motor through pipes 20. 105

The motor-shaft 15 extends forward beyond the hood 13 and frame 12 to receive the

usual starting-crank and is provided with a rearward extension 21, formed in one piece with or suitably coupled thereto or otherwise driven therefrom, said shaft 21 being supported in suitable bearings 22 on the body 1. This shaft 21 extends centrally and longitudinally of the body of the vehicle to a point adjacent to the seat, at which latter point there is located a transverse shaft 23, supported in bearings 24, carried by brackets 25, secured to the angle-bars forming the frame 11. This transverse shaft 23, preferably located under the seat, constitutes the main driving-shaft, from which the driving-wheels 7 are driven. To actuate said main driving-shaft from the engine-shaft, the shaft 21 has splined thereon a beveled friction-pinion 26. This pinion, which is thus movable longitudinally on the shaft 21 while rotating in unison with the same, is controlled by a hand-lever 27, pivoted under the seat, as indicated at 28. One end of the hand-lever 27 is bent downward, as indicated at 29, and has a forked extremity 30, which engages a grooved collar 31 on one end of the pinion 26. The other end of the lever 27 is bent upward, as indicated at 32, to a form a handle and is provided with the usual locking-segment 33 and locking mechanism 34 to secure it in any position to which it may be adjusted. The shaft 23 has splined thereon two conical friction wheels or disks 35 and 36, connected by a sleeve 37 so as to move in unison. These friction disks or cones are thus movable longitudinally of the main driving-shaft 23 while rotating in unison therewith, and their movement along said shaft is controlled by means of a hand-lever 38, provided with the usual locking-segment 39 and locking mechanism 40 to secure it in adjusted position. To this hand-lever there is pivoted one end of a link 41, the other end of which is pivoted to one arm of a bell-crank lever 42. The other end of the bell-crank lever is connected by a link 43 to a collar 44, mounted in a groove in the hub or sleeve extension 45 of the friction cone or disk 36. The construction is such that the collar 44 does not rotate with the part on which it is mounted, but serves 50 through the mechanism described to shift the friction-cones to any desired position longitudinally of the shaft 23.

It will be understood that the motor 14, as usual in vehicles of this type, runs continuously in the same direction and at about the same speed when at work. The direction of movement and speed of the vehicle are dependent upon the direction of movement and speed of the shaft 23, from which the driving-wheels are driven in the manner hereinafter described, and the direction and speed of the shaft 23 are controlled by the friction-gearing just described, for it will be seen that when the shaft 21 is rotating in the direction in which it is driven by the motor, which direction

is indicated by the arrow in Fig. 3, the friction cones or disks 35 and 36 may be shifted along the shaft 23 by means of the lever 38, so as to bring either one of said cones into contact with the pinion 26. If the friction-cone 35 is brought into contact with the pinion 26, the shaft 23 will rotate in one direction, while the bringing of the cone 36 into contact with the pinion 26 will cause the shaft 23 to rotate in the opposite direction. The speed of rotation in either direction may be varied by shifting the pinion 26 longitudinally on the shaft 21, so as to bring it into contact with the cone which it is driving at different points, nearer to or farther from the axis of rotation of the shaft 23. It will be at once seen that when this point of contact is farthest from said axis the speed of the shaft 23 will be slowest, such speed increasing as the point of contact is shifted nearer to said axis by shifting the pinion 26 rearward on its shaft. Thus the setting of the pinion 26 at any desired point determines in a general way the speed. The shifting of the cones 35 and 36 by means of the lever 38 may be utilized to stop, start, and reverse the direction, also in a measure controlling the speed by controlling the extent of the pressure with which the cone is forced against the pinion. Any given position of the pinion 26 determines a maximum speed, and practically any speed below that maximum to a complete stoppage may be obtained by using the lever 38 to press one of the cones 35 or 36 against the pinion 26 of any desired pressure, the maximum pressure insuring the maximum speed for a given position of the pinion 26, while less pressure will permit a variable amount of slip between the friction-surfaces, thereby reducing the speed as desired.

Motion is transmitted independently to each of the driving-wheels 7 from the shaft 23 by means of sprocket-chains 46, passing over sprocket-wheels 47 on the shaft 23 and sprocket-wheels 48 on the driving-wheels 7. The sprocket-wheels 47 are mounted loosely on the shaft 23 and are connected therewith by clutches 49, so constructed that when the shaft 23 rotates in what may be termed a "forward" direction said clutches drive the sprocket-wheels and cause them to rotate in unison with said shaft, while at the same time the driving-wheels are free to rotate independently of each other in a forward direction, as is necessary in following a curved path, as in turning. Provision is also made for locking one of these clutches to its sprocket-wheel when the shaft 23 is rotated in the reverse direction, as in backing the vehicle, so that the sprocket-wheel will positively rotate with the shaft and cause the driving-wheel to which it is connected to rotate in the same direction, the backing being thus accomplished by the application of power to one of the driving-wheels only, leaving the

other free. Each clutch 49 comprises a pawl-bearing member 50, secured on the shaft 23, and having in its periphery recesses 51, in which are pivoted the pawls 52, which latter are preferably four in number. This pawl-bearing member is inclosed by a ratchet-bearing member 53, having on its internal periphery ratchet-teeth 54, with which the pawls 52 engage. The sprocket-wheels 47 are secured to or formed in one piece with the ratchet-bearing members 53, which latter are loosely mounted upon the shaft 23.

From an examination of Fig. 5 of the drawings it will be seen that the ratchet-teeth are not spaced equidistantly with the pawls, but are so arranged that when one tooth is in full engagement with a pawl the next pawl is about one-fourth of the length of a tooth from engagement, the next pawl 20 one-half of such length, and the last pawl three-fourths of such length. It results from this construction that quick engagement of the pawl-bearing member with the ratchet-bearing member is obtained, since 25 in any position of the parts it cannot require a movement of more than one-fourth of the length of a tooth to engage the clutch members. The pawls 52 are preferably freely swinging pawls not provided with springs for 30 forcing them outward, but acting by centrifugal action, and thereby avoiding the noise or clicking which occurs with spring-pressed pawls when the ratchet member is running past the pawl-bearing member. I have, 35 however, shown the pawl-bearing member 50 as provided with recesses 55, in which may be inserted springs for acting upon the pawls 52, if desired.

As already stated, provision is made for 40 locking one of the clutches in backing, and this provision is of such a nature that said locking is automatically accomplished by the shifting of the disks or cones 35 and 36 so as to bring the reversing-cone 36 into contact 45 with the pinion 26. To this end the disk 35 or the sleeve 37 is provided with a hub or extension 56, grooved to receive a fork 57 on one end of a rod 58, which extends parallel with the shaft 23 and is supported in suitable 50 guides 59. The outer end of this rod 58, adjacent to the left-hand clutch 49, is provided with a similar fork 60, which engages a grooved collar 61, mounted to slide longitudinally on the shaft 23. The collar 61 is provided with an outwardly-projecting pin 62, which extends into an aperture 63 in the pawl-bearing member 50 of the clutch. The ratchet-bearing member 53 of the clutch is provided with a recess or aperture 64, into 55 which the end of the pin 62 is projected when the sleeve 37 is moved upon the shaft 23 so as to bring the reversing-cone 36 into contact with the pinion 26. By reason of this construction the act of shifting the sleeve 60 over to bring the reverse-gearing into mesh

serves to lock the clutch members on the left-hand side of the machine, and thereby cause the driving-wheel 7 on that side of the machine to be positively driven in a direction proper to cause the vehicle to back.

The driving-wheel sprockets 48 are connected to the driving-wheels by the means shown more particularly in Figs. 4 and 6 of the drawings. Since these wheels are the ordinary buggy or road-wagon wheels having the usual wooden hub and spokes, it is necessary to make some provision whereby the sprocket-wheels may be firmly connected thereto, but readily detached. To this end I employ a sprocket-wheel having a body 8c portion 65 with an annular portion 66, on which the separate rim 67 of the sprocket-wheel is seated, and a flange 68, to which said rim is secured by bolts 69. This body is therefore adapted to receive rims having 85 different numbers of teeth and permits the removal of the rim in case of breakage of the teeth and the substitution of another rim. The body 65 has extending outwardly from the annular portion 66 arms 70, to the outer 90 ends of which is connected a sleeve 71, which fits on the hub 72 of the driving-wheel. This sleeve 71 has outwardly-extending fingers or projections 73, which pass between the spokes 74 of the driving-wheel. 75 indicates a ring fitted on the body of the hub 72 outside of the spokes 74, said ring being provided with a flange 76, through which pass screw-bolts 77, which serve to connect the extensions or fingers 73 to the ring 75, and thereby detachably secure the body of the sprocket-wheel in position on the hub. By 100 reason of this construction the sprocket-wheels may be readily applied to and removed from the ordinary vehicle-wheels.

The steering, as already stated, is accomplished by means of the front wheels 10, which are pivotally supported by the usual fifth-wheel construction 9 or some other similar central pivotal support. The axle 8 has connected to it near each end the extremities of a curved rack-bar 78, which extends rearward from said axle in substantially semicircular form and horizontally. The connection is preferably effected by means 115 of U-shaped bolts or clips 79, which pass upward around the axle, through the ends of the rack-bar, and are secured by nuts 80. The rack-bar is preferably in the form of a cylindrical tube bent to the desired form and having formed in its inner curved face apertures 81 to receive the teeth of the steering-pinion.

82 indicates a guide secured to the under side of the body 1 and provided with grooved guide-rollers 83, between which the rack-bar fits and is supported.

84 indicates the steering-shaft, which is supported in a suitable bearing 85 on the body 1 and is provided at its upper end with a hand-

wheel 86 within convenient reach of the operator when seated upon the seat 2. The lower end of the steering-shaft 84 is provided with a pinion 87, the teeth of which enter the apertures 81 in the rack-bar, and thereby serve to so move the same as to give the steering-wheels 10 the position necessary to guide the vehicle in the desired direction.

It will be seen that the construction is such that the parts required to convert an ordinary road-wagon or buggy into a motor-vehicle can be readily applied to such road-wagon, thereby rendering such conversion a readily-effected one. The additional structural elements are comparatively simple, inexpensive, and light, and by their application to a road-wagon a satisfactory motor-vehicle or automobile can be obtained at a relatively slight expense. The driving mechanism is simple, efficient, and capable of giving a relatively great range of finely-graduated speeds in either direction, while the steering mechanism is equally simple and efficient.

I do not wish to be understood as limiting myself to the precise details of construction hereinbefore described, and shown in the accompanying drawings, as it is obvious that these details may be varied without departing from the principle of my invention.

Having thus fully described my invention, what I claim as new, and desire to secure by Letters Patent, is—

1. In combination with the body and running-gear of a road-wagon or similar vehicle, a strengthening and supporting frame adapted for connection to the body of the vehicle, a motor supported on said frame, a longitudinally-extending shaft driven by said motor, a transverse shaft provided with clutch-connected sprocket-wheels at its ends, other sprocket-wheels adapted for connection to the rear wheels of the running-gear, sprocket-chains connecting said sprocket-wheels, and controlling-gearing connecting said shafts, substantially as described.

2. In combination with the body and running-gear of a road-wagon or similar vehicle, a strengthening and supporting frame adapted for connection to the body of the vehicle, a motor supported on said frame, a longitudinally-extending shaft driven by said motor, a transverse shaft provided with clutch-connected sprocket-wheels at its ends, other sprocket-wheels adapted for connection to

the rear wheels of the running-gear, sprocket-chains connecting said sprocket-wheels, and controlling-gearing connecting said shafts, said controlling-gearing comprising a friction-pinion rotating with and movable lengthwise of the longitudinal shaft, two oppositely-arranged friction-disks rotating with and movable longitudinally on the transverse shaft, and means for shifting said pinion and disks, substantially as described.

3. In combination with the body and running-gear of a road-wagon or similar vehicle, a strengthening and supporting frame adapted for connection to the body of the vehicle, a motor supported on said frame, a longitudinally-extending shaft driven by said motor, a transverse shaft provided with clutch-connected sprocket-wheels at its ends, other sprocket-wheels adapted for connection to the rear wheels of the running-gear, sprocket-chains connecting said sprocket-wheels, controlling-gearing connecting said shafts, and steering mechanism comprising a curved rack adapted for attachment to the front axle, and a steering-shaft provided with a pinion to mesh with said rack, substantially as described.

4. In a vehicle of the character described, the combination, with the box-body, of a strengthening and supporting frame consisting of an angle-bar bent to form parallel portions fitting and secured to the lower side edges of the body and having an extension projecting in front of said body to form a support for the motor said extension being in a plane lower than the main portion of said supporting-frame, substantially as described.

5. In a vehicle of the character described, the combination, with the box-body, of a strengthening and supporting frame consisting of an angle-bar bent to form parallel portions fitting and secured to the lower side edges of the body and having an extension projecting in front of said body and bent downwardly and then outwardly to form a support for the motor, said forwardly-extending portion being depressed, substantially as described.

In testimony whereof I affix my signature in presence of two witnesses.

EDWARD TEMPLE
